N. J. MACDONALD.
FLOOR.
APPLICATION FILED SEPT. 18, 1917.

1,272,826.

Patented July 16, 1918.

UNITED STATES PATENT OFFICE.

NORMAN JOHN MACDONALD, OF WINNIPEG, MANITOBA, CANADA.

FLOOR.

1,272,826.

Specification of Letters Patent. Patented July 16, 1918.

Original application filed July 28, 1916, Serial No. 111,928. Divided and this application filed September 18, 1917. Serial No. 191,990.

To all whom it may concern:

Be it known that I, NORMAN JOHN MACDONALD, of the city of Winnipeg, in the Province of Manitoba, Canada, have invented certain new and useful Improvements in Floors, of which the following is the specification.

The invention relates to improvements in floors and the object of the invention, which 10 is a division from application Number 111,928, filed July 28, 1916, is to provide an inexpensive easily constructed floor which can be quickly set up when required for use and as easily taken down for shipping or 15 storage purposes and while providing a floor of this type, construct it so that it will be tight fitting, which feature is an important one as will readily be appreciated.

A still further object of the invention is 20 to construct a floor which requires no nailing or similar permanent fastenings when being set up, and while avoiding these, to supply a rigid structure serviceable as a flooring.

25 With the above objects in view the invention consists essentially in a substantially rectangular take-down frame, a floor formed from floor boards insertable within the frame, filling strips associated with the floor 30 boards and floor joists or sleepers passing lengthwise of the frame and beneath the floor boards the parts being arranged and constructed as hereinafter more particularly described and later pointed out in the appended claims, reference being had to the 35 accompanying drawing in which:—

Figure 1 represents a perspective view of a floor constructed in accordance with my invention, parts of the floor being broken 40 away to expose construction.

Fig. 2 represents an enlarged detailed perspective view of one of the corner joints of the frame, the said joint being pulled apart.

Fig. 3 represents a vertical sectional view 45 through the floor at the end.

I have found that there is considerable demand for a collapsible or knockdown floor which can be utilized for camping purposes season after season or as the floor of a sectional house and in order to supply such a demand I have invented the present floor which can be manufactured cheaply, can be set up or taken down quickly and is of such a nature that it can be shipped or stored 55 very conveniently.

Referring now to the drawing in which

like characters of reference indicate corresponding parts in the several figures.

1 represents a substantially rectangular floor frame formed from similar side members 2 and 3 and similar end members 4 and 5. The said side and end members are actually made from a body or main strip 6, to the top and bottom sides of which 1 permanently fasten, such as by nailing, equal width 60 top and bottom strips 7 and 8, the outer edges of the latter strips lying flush with the outer edge of the main strip while the inner edges of the top and bottom strips overhang the inner edge of the body strips and form 70 with it a channel 9.

It will here be observed that the main strips of the end members 4 and 5 are somewhat longer than the attached top and bottom strips so that they project in extensions 6' and 6'' which are adapted to be received between the extending ends 7' and 8' of the top and bottom strips of the side members of the frame. 75

From the above construction it will be obvious that the frame members can be quickly put together by fitting the extending ends 6' and 6'' of the end members between the extensions 7' and 8' of the side members and holding them together by inserting 80 85 through the openings 10, corner bolts 11.

In this connection it is to be noticed that once the corner bolts are inserted the frame is more or less a rigid one as the manner in which the corners go together provides a 90 tight fitting corner once the bolt is inserted.

The end members of the frame are arranged to lie on floor joists or sleepers 12, which joists have their ends rabbeted away 95 as indicated at 12' to receive the lower cross strips of the end members 4 and 5 in such a manner that their upper faces will lie flush with the upper faces of the said cross strips. The joists are held to the end members by inserting bolts 13 through the joists and the 100 end members, registering openings being provided.

Within the frame I insert floor boards 14 which floor boards pass in a direction at right angles to the joists on which they lie. 105 The floor boards are all of an equal length and are so adapted that when in position their ends lie in the channels of the side members 2 and 3. In connection with the insertion of these floor boards within the 110 frame, I may mention that I have found it desirable to enter them through a side open-

ing 15 reserved in one of the side members of the frame. This opening is actually made by cutting away a portion of the body strip 6. By providing this opening it will be seen 5 that I am able to set the frame up on the joists and then put the floor boards in position by threading them, so to speak, through the opening 15 until the ends thereof take their positions in the channels and 10 then sliding the boards one after the other in opposite directions to the ends of the frame.

In the drawing I have shown the last board to be inserted as only partially in and 15 I have also shown the inner or advanced end of this board with its sides slightly cut away to provide a more or less wedge shaped or driving end 14*. This arrangement allows of the easy entering of the last floor board to 20 be laid and also permits of the effective tightening up of the floor, as after the pointed end of the last floor board has been inserted through the opening it can be driven in by a mallet to close the cracks in the 25 floor.

After the floor boards have been placed in position filling strips 16 are inserted within the channels above the floor boards and beneath the overhanging portions of the top 30 strips of the frame members.

From the above disclosure it will be readily apparent that this floor can be very quickly set up and as easily taken apart and that it requires no special tools to lay it and 35 further that it is a particularly neat, light, convenient and durable floor for camping or other similar purposes.

While I have described one, and possibly the most preferable, manner of setting up 40 the floor still it will be understood that this is not the only way it can be set up in a quick and efficient manner as obviously the frame could be set up with one of the side members removed and the floor boards could 45 be placed in position on the attached joists and then the removed side piece could be finally placed in position on the ends of the boards.

In connection with the tightening up of 50 the floor I wish to point out that in instances where it is found that the floor has shrunk or swollen through weather conditions one can take up irregularities by inserting narrow strips in the grooves at the ends of the 55 floor boards, which strips would not be seen in the completed floor and would allow of the proper tightening up of the cracks in the floor when the last floor board was being driven in.

60 What I claim as my invention is:—

1. In a portable house a take-down floor

comprising a substantially rectangular frame formed from side and end members detachably connected and formed to provide a continuous channel at the inner side of the frame, equal length floor boards crossing the frame and having their ends received within the channels of the side members, floor joists passing lengthwise of the frame beneath the floor and having their ends detachably secured to the end members of the frame and filler strips inserted in the channels above the floor boards.

2. In a portable house a take-down floor comprising a substantially rectangular frame formed from side and end members jointed at the corners and releasably fastened together and constructed to provide a continuous channel passing around the inner side of the frame, there being an entrance opening reserved in one of the side members of the frame to admit of entrance to the channel, equal length floor boards insertible in the frame through the entrance opening and having their ends received within the channels of the side members of the frame, joists passing lengthwise of the frame and located beneath and supporting the cross boards and having their ends detachably secured to the end members of the frame and filling strips inserted in the channel above the floor boards.

3. In a portable house a substantially rectangular take-down frame comprising side and end members releasably connected at the corners and constructed to present a continuous channel at the inner side of the frame and provided with an entrance opening to the channel through one of the side members.

4. In a portable house a substantially rectangular take-down floor frame comprising side and end members formed each from body strips and applied top and bottom strips, the inner edges of which extend beyond the body strips and provide a continuous channel at the inner side of the frame and having the body strips of the end members projecting beyond the ends of the top and bottom strips thereof and the top and bottom strips of the side members projected beyond the body strips thereof, and means releasably fastening the projected ends of the side top and bottom strips to the inserted projected ends of the body strips of the end members of the frame.

Signed at Winnipeg, this 16th day of August, 1917.

NORMAN JOHN MACDONALD.

In the presence of—

G. L. ROXBURGH,

K. B. WAKEFIELD.
